CLAIM

The ornamental design for a pediatric umbilical hernia support belt as shown and described.

DESCRIPTION

FIG. 1 is a perspective view of a pediatric umbilical hernia support belt showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the pediatric umbilical hernia support belt of FIG. 1, shown in condition of use for clarity of disclosure;

FIG. 9 is a left side elevational view thereof;

FIG. 10 is a front elevational view thereof; and,

FIG. 11 is a rear elevational view thereof.
